UNITED STATES PATENT OFFICE.

FRED J. HEIDEMAN, OF DETROIT, MICHIGAN, ASSIGNOR, BY DIRECT AND MESNE ASSIGNMENTS, TO HOUSEHOLD UTILITIES CORPORATION, OF DETROIT, MICHIGAN, A CORPORATION OF DELAWARE.

EXPANSION VALVE FOR REFRIGERATING APPARATUS.

Application filed January 30, 1920. Serial No. 355,054.

To all whom it may concern:

Be it known that I, FRED J. HEIDEMAN, a citizen of the United States, residing at Detroit, in the county of Wayne and State 5 of Michigan, have invented a new and useful Expansion Valve for Refrigerating Apparatus, of which the following is a specification.

This invention relates to expansion valves 10 for refrigerating apparatus, and more particularly for small thermostatically controlled refrigerating plants for household use.

The invention consists primarily in the 15 formation of a differentially stressed diaphragm and in the employment of a spring reinforcing member for said diaphragm through which automatic control of the valve is exercised, a more satisfactory functioning of the diaphragm being thus secured.

The invention further consists in the various features and arrangement of parts hereinafter fully described and illustrated 25 in the accompanying drawing wherein,

Fig. 1 is a view in side elevation of the valve.

Fig. 2 is a vertical sectional view of the same.

Fig. 3 is an interior view of the diaphragm prior to its engagement with the valve casing.

In these views the reference character 1 designates a portion of the refrigerating 35 apparatus which serves as a support for the expansion valve, this portion preferably being the brine tank. The casing of the valve comprises a sheet metal diaphragm 2 having a down-turned peripheral rim 3, and a cast 40 metal base member 4 having an upwardly projecting rim 5 formed exteriorly with an annular bead 6 over which the lower edge portion of the diaphragm rim 3 is rolled, as indicated at 7. A circular chamber 8 is formed between the members 2 and 4, and the latter member is provided with inlet and outlet passages for said chamber, numbered 9 and 10 respectively. The outlet passage 10 extends through a lug or boss 50 11, depending from the base member 4 and which is screw-threaded to engage a fitting 12 carried by the tank 1, said boss thus supporting the valve casing. The valve member 13 is of hemispherical shape and is dis-

posed in the passage 9 centrally beneath the chamber 8, normally closing an upturned outlet 14 of said passage, which forms an inlet port for said chamber 8. The stem 15 of said valve member passes upwardly through the port 14, chamber 8 and diaphragm 2, and is threaded for adjustment through a hub 15^a which centrally surrounds the diaphragm. To insure against leakage around said stem, a packing nut 16 engages the outer end of the hub and compresses suitable packing 17 about the stem. The stem is passed through said packing nut and its end is squared, as indicated at 18, for engagement by a wrench or the like.

Within the chamber 8 there is disposed a 70 flat upwardly dished leaf spring 19 reinforcing the diaphragm 2, and having the shape of a star or spider, as is best disclosed in Fig. 3. The several radial arms of said spring bear upon the rim 5 and the center portion bears against the center of the diaphragm and is rigidly secured thereto. It is preferred to employ a common means for securing the hub 15^a and said spring to the diaphragm, this being accomplished by extending a reduced end portion of the hub centrally through the diaphragm and spring, and up-setting said portion to engage beneath the spring, as indicated at 20.

In order to avoid any undue stiffening of the diaphragm at the marginal portion of its periphery resulting from the reinforcing effect of the formation of the rim thereon, said marginal portion is reduced in thickness by the formation of a slight annular 90 depression 21 in the interior face of the diaphragm adjacent said rim, thus weakening such portion and effecting a differential stressing of the diaphragm which renders it more effectively flexible throughout the 95 greater area thereof.

As will be readily understood by persons familiar with this art, at intermittent periods a pump (not shown) sets up a suction or sub-atmospheric pressure in the chamber 8, and delivers a liquid refrigerant to the passage 9. When such conditions exist the diaphragm is inwardly deflected (due to the greater exterior pressure exerted by the atmosphere) and the valve 13 is unseated, permitting a very limited flow of the liquid refrigerant into the chamber 8. The low pressure conditions there encountered cause

an immediate transformation of the liquid into gas, and as such it is withdrawn through the passage 10. During idle periods the spring reinforces the stresses acting in the diaphragm, itself, to insure an outward deflection of the latter, and the consequent seating of the valve member. Heretofore it has been quite a delicate matter to mount the diaphragm so that the stresses created by its inward deflection would immediately insure a reverse deflection upon approximate equalization of interior and exterior pressures. Thus, if the diaphragm were permitted to deflect inwardly slightly beyond the plane of its periphery, the resulting stresses might not be sufficient to effect the return movement. By employing a reinforcing spring, in accordance with the present invention, the outward or return movement of the diaphragm is assured, even though it may be deflected beyond its intermediate position. Furthermore, the diaphragm, when so formed and reinforced, may be made more readily responsive to a pressure differential, being proportioned to flex more readily than is feasible where the internal stresses of the diaphragm are alone relied upon to effect its return movement.

30 What I claim is:

1. In an expansion valve for refrigerating apparatus, a casing having an expansion chamber and an inlet thereto and outlet therefrom, and a diaphragm forming a wall of said chamber, a valve controlling said inlet, actuatable by said diaphragm, and normally seated thereby, and a spring within said chamber acting on said diaphragm and assisting its return to normal after deflection.

2. In an expansion valve for refrigerating apparatus, a casing having an expansion chamber and an inlet thereto and outlet therefrom, and a diaphragm forming a wall of said chamber, a valve controlling said inlet, actuatable by said diaphragm, and normally seated thereby, and a spider-shaped spring within said chamber acting on said

diaphragm and assisting its return to normal after deflection, said spring being centrally secured to said diaphragm and peripherally bearing upon the casing.

3. In an expansion valve for refrigerating apparatus, a casing having an expansion chamber and an inlet thereto and outlet therefrom, and a diaphragm forming a wall of said chamber, a valve controlling said inlet, actuatable by said diaphragm and normally seated thereby, and means within said chamber supplementing the internal stresses of the diaphragm in resisting deflection thereof from normal and in effecting a return movement.

4. In an expansion valve for refrigerating apparatus, a casing having an expansion chamber and an inlet thereto and outlet therefrom, and a diaphragm forming a wall of said chamber, a valve controlling said inlet, actuatable by said diaphragm and normally seated thereby, a stem for said valve passing through the diaphragm, a hub exteriorly surmounting the diaphragm, in which hub said stem is adjustable, a spring within said chamber resisting deflection of the diaphragm from normal and assisting the return movement thereof, and a common means for securing said hub and said spring to said diaphragm.

5. An expansion valve for refrigerating apparatus comprising a casing having an expansion chamber formed between two members, one of which has an intake and an outlet passage for said chamber and the other is in the nature of a flexible diaphragm, a valve controlling said inlet passage, a connection between said valve and diaphragm for actuating the former from the latter, and a spider shaped dished spring within said chamber centrally bearing against said diaphragm and peripherally engaging the other member of the casing, said spring assisting the diaphragm in its return to normal position.

In testimony whereof I sign this specification.

FRED J. HEIDEMAN.
